UNITED STATES PATENT OFFICE.

PHILIP W. MOORE, OF EVANSTON, ILLINOIS, ASSIGNOR TO THE P. & M. CO., OF CHICAGO,
ILLINOIS, A CORPORATION OF ILLINOIS.

ANTICREEPER.

1,267,786.

Specification of Letters Patent.

Patented May 28, 1918.

Application filed June 5, 1915. Serial No. 32,288.

To all whom it may concern:

Be it known that I, PHILIP W. MOORE, a citizen of the United States, residing at Evanston, in the county of Cook and State of Illinois, have invented new and useful Improvements in anticreepers, of which the following is a full, clear, concise, and exact description, reference being had to the accompanying drawing, forming a part of this specification.

My invention relates to improvements in means for preventing the longitudinal movement or creeping of railhead rails, such devices being known as anti-creepers or rail anchors. Some of the features disclosed in the construction illustrated herein are covered by the claims of my Patent No. 1,140,345, issued May 18th, 1915, and of my Patent 1,175,653, issued March 14, 1916. The general object of the present invention is to provide an improved one-piece anti-creep. Other objects are to provide an anti-creep which fits over both flanges of the rail base and is positively held to the rail by a pin which has a driving fit in an opening therein; to provide an improved anti-creep of the type which increases its grip on the rail base by a tilting action about a transverse horizontal axis; to provide an anti-creep which cannot be removed from the rail without deforming it after it is once applied thereto; and to provide an effective anti-creep of generally simplified construction.

The embodiment of the invention shown in the accompanying drawing will serve to illustrate the various features involved. Numerous other embodiments of the invention may be devised.

Figure 1 is a rear elevation of the anti-creep, the rail being shown in end elevation.

Fig. 2 is a top plan view of said anti-creep.

Fig. 3 is a side elevation thereof in inclined position as it is being applied to the rail base.

The rail anchor, in the form illustrated, consists of a single casting, preferably of malleable iron, part of which may therefore be bent without breaking, for a purpose hereinafter explained. The device comprises a transverse element or cross-piece 1 adapted to be located beneath the rail base and having extensions or jaws 2, 3 at oppo-

site ends thereof, the whole forming what may be termed a yoke. Said jaws are suitably reinforced by flanges 4, 5 respectively which are extended downwardly to form tie-abutting extensions 6, 7. These latter are further reinforced by webs 8, 9 respectively.

The jaws 2, 3 are located considerably in advance of the cross-piece 1, reference being had to the direction of creeping as indicated by the arrow. When the anchor is positioned on the rail 10, the creeping thrust produces a tendency for the rail anchor to tilt about a horizontal axis transverse to the length of the rail. The under parts of the jaws 2, 3 bear downwardly against the top 70 of the base flanges of the rail, and the upper surface of the cross-bar 1 bears upwardly against the base thereof. This action causes the base flanges to be gripped firmly by said jaws and said cross-bar, the frictional engagement of said parts with said rail base being sufficient to resist the creeping thrust. The forward movement of the rail is resisted, of course, by the tie 11 to which the creeping thrust is transmitted by the rail anchor. 80

The upper wall of the jaw 3 is extended to form an arm 12 having an opening 13 therein. Said arm, before the device is applied to the rail base, assumes the position shown in Fig. 1. After the anchor is applied thereto, it is bent down by hammer blows to the position shown in dotted lines in said figure. One side of the rail base is engaged by the vertical walls 14, 15 and the other side is engaged by the vertical 90 walls 16, 17 whereby the anchor is restrained against lateral movement, independently of the arm 12. Said walls 16, 17 constitute parts of two abutments or ribs located one considerably in advance of the other. The 95 surfaces, when seen projected from the rear, as in Fig. 1, appear to almost meet, the opening in the jaw 3 being apparently too small to admit the base flange. However, said abutments are not located immediately 100 one over the other, but one considerably in advance of the other as previously stated, and the intermediate portion of the material is cut away at 18. With this construction, the side of the base flange may be received 105 within the jaw 3 if the anchor is tilted to about the position shown in Fig. 3. In assembling the rail anchor, therefore, it is necessary first to so tilt it, in which position it may be applied to one base flange of 110

the rail with the edge of the base adjacent to the vertical wall of the jaw 3. In this position, the other jaw 2 may be lifted until the cross-piece engages the bottom of the rail base. The entire structure is then shifted laterally until the rail base engages the vertical wall 14 of the jaw 2. In this position, the opposite side of the rail base will clear or fall within the plane of the surfaces 16, 17. The rail anchor may now be swung to vertical or normal position, whereupon it will be positively engaged between the walls 14, 15 and 16, 17. The creeping thrust of the rail anchor will keep it in this position. However, to lock it in place, the arm 12 is bent downwardly as previously explained. The anchor thus deformed, cannot be removed from the rail. It cannot be moved laterally, as long as it is upright, and it cannot be tilted as the arm fits against the top of the rail base flange. To positively lock the anchor to the rail, a pin 19 is driven through the opening 13 and through an alined opening in the web of the rail. In drilling the hole, the arm 12 with its opening, may be used as a templet. The hole drilled is of small diameter being preferably the size ordinarily used in securing bond wires to the rails, and the pin is a driving fit. The pin connection just described insures the maintenance of the rail anchor in upright position. Even if the rail should retract and the flanges 6, 7 be frozen in the ballast, said rail anchor would not tilt readily to such position as to relax its hold, but would continue to engage the rail base, since any pivoting of the arm 12 about the pin 19 would cause the lower part of said arm to bind against the upper surface of the rail base. If the ballast failed to yield, the anchor would thus resist creeping in a rearward direction also.

The invention is not limited to the particular embodiment described herein except where limitations appear in the appended claims. The device need not necessarily be made as a casting or with the relative proportions and arrangement of parts illustrated. I desire to cover, therefore, whatever suitable equivalent means may be devised which fall within the scope of said claims.

Having thus described my invention, what I claim as new and desire to secure by Letters Patent of the United States is:

1. The combination with a railroad rail having an opening therein, of a one-piece anti-creeper fitting over both sides of the rail base and provided with a pin of such size as to have a driving fit in said opening to aid in securing said rail anchor in place.

2. An anti-creeper comprising integral means for engaging the opposite flanges of a rail base both above and below the same, means engaging a tie to transmit the creep-

ing thrust thereto and to insure a tilting action whereby the rail base is firmly gripped by said anti-creeper, and an extension on one of said rail engaging means having positive engagement with the rail to prevent tilting in a direction which would relax the grip on the rail base. 70

3. A rail anchor comprising a yoke having an extension at each end thereof, the extension at one end fitting against the top, side and bottom of the base flange, the extension at the other end also fitting against the top, side and bottom of the opposite base flange, but being cut away to provide a clearance sufficient to admit said base flange when said anti-creeper is tilted, and means for preventing tilting. 75

4. An anti-creeper comprising a body portion which bears against the bottom of the rail, a pair of gripping members integral with said body portion and extending upward above the plane of said body portion, a depending member integral with said body portion, said depending member and gripping members being in substantially a vertical plane and in advance of said body portion and an extension on one of said gripping members co-operating with the rail to prevent movement of the anti-creeper in a direction to decrease its effectiveness. 85

5. An anti-creeper comprising a single member shaped to fit against the bottom of the rail and over the base flanges thereof and bear against the side of a tie, the portion bearing against the bottom of the rail being to the rear, both of the portions fitting over the base flanges and the portion bearing against said tie, and an integral extension co-operating with said rail for maintaining said anti-creeper in position. 90

6. An anti-creeper comprising means which fit one side of the rail base, a downwardly extending flange beneath the side of the rail base which bears against the tie and an integral extension on the upper part of said means normally clearing the web of the rail and arranged to be bent adjacent to said web after the anchor is positioned. 100

7. A rail anchor comprising a jaw fitting one side of a rail base, a tie-abutting flange beneath said jaw, an extension on said jaw having an opening therein, means passing through said opening for locking said anti-creeper to the rail, and an integral extension having positive engagement with the opposite side of the rail base. 115

8. A rail anchor comprising a yoke consisting of a cross-piece having upwardly and inwardly turned extensions at opposite ends thereof arranged to grip the rail base, one of said extensions providing a clearance which permits the anti-creeper to be moved laterally with respect to the rail, said anti-creeper having a portion arranged to be bent to engage said rail thereby obstructing 120

125

said lateral movement and preventing the removal of the rail anchor from the rail.

9. An anti-creeper comprising a cross-bar, an abutment at each end thereof providing a pair of vertical walls between which the rail base fits, forward extensions on the ends of said cross-bar arranged to fit over the top of the rail base, and a downwardly extending flange at the forward end of each of said extensions.

10. An anti-creeper comprising a cross-bar having a forward extension at each end thereof, each of said extensions having two vertical surfaces in the same plane arranged to fit against the side of the rail base, said surfaces on each side being spaced apart longitudinally, one of said forward extensions being cut away between the front and rear surfaces sufficiently to receive the rail base when the anchor is tilted.

11. An anti-creeper comprising a single member having jaws which fit the opposite sides of the rail base, the rail having an

opening therein, an extension on one of said jaws having an opening therein and a pin 25 passing through said latter opening and having a driving fit in said first opening.

12. The combination with a railroad rail having an opening therein, of an anti-creeper which grips both sides of the rail 30 base, an extension on one side of said anti-creeper having an opening therein alined with said first opening, and a locking pin passing through said alined openings.

13. The combination with a railroad rail, 35 of a rail anchor having means for frictionally gripping both sides of the base thereof, and a pin fitting within an opening in said rail, said pin being independent of said anti-creeper but co-operating therewith to 40 prevent movement in such a direction as to relax the hold thereon on the rail base.

In witness whereof, I have hereunto subscribed my name this 2nd day of June, 1915.

PHILIP W. MOORE
